UNITED STATES PATENT OFFICE

147,825

DESIGN FOR A SUITCASE

Robert B. Wemyss, Louisville, Ky., assignor to Reynolds Metals Company, Richmond, Va., a corporation of Delaware

Application November 9, 1946, Serial No. 134,678

Term of patent 14 years

(Cl. D87—5)

To all whom it may concern:

Be it known that Robert B. Wemyss, a citizen of the United States, residing in Louisville, county of Jefferson, State of Kentucky, has invented a new, original, and ornamental Design for a Suitcase, of which the following is a specification, reference being had to the accompanying drawing, forming part thereof, wherein—

Figure 1 is a perspective view of the suitcase showing my new design, the design being alike as to both major faces, and both ends;

I claim:

The ornamental design for a suitcase, substantially as shown and described.

ROBERT B. WEMYSS.
